UNITED STATES PATENT OFFICE.

WILHELM FRIEDRICH LÖFFELHARDT, OF HAMBURG, GERMANY.

ALARM APPARATUS.

SPECIFICATION forming part of Letters Patent No. 376,989, dated January 24, 1888.

Application filed July 22, 1887. Serial No. 245,002. (No model.) Patented in Germany August 20, 1884, No. 31,285; in England August 20, 1884, No. 11,473, and in France August 21, 1884, No. 163,873.

To all whom it may concern:

Be it known that I, WILHELM FRIEDRICH LÖFFELHARDT, a subject of the German Emperor, and a resident of Hamburg, in the German Empire, have invented certain new and useful Improvements in Alarm Apparatus, (for which I have received Letters Patent in Germany, No. 31,285, dated August 20, 1884; in France, No. 163,873, dated August 21, 1884; and in Great Britain, No. 11,473, dated August 20, 1884,) of which the following is a specification.

My invention relates to improvements in apparatus for announcing either the closing or opening of doors, drawers, &c.; and the objects of my improvements are either to stop the alarm entirely or to make it sound while the driving mechanism moves one way or moves to and fro. I attain these objects by the mechanism illustrated in the accompanying drawings, in which—

Figures 1, 2, and 3 are top views of an apparatus, with the bell removed therefrom, in different positions of the working parts. Fig. 4 is a cross section on the dotted line x x , Fig. 3. Figs. 5 to 9 illustrate details. Fig. 10 shows the application of the apparatus to a door.

Similar letters refer to similar parts throughout the several views.

The hammer i is pivoted upon a movable disk, e' , and is worked by a fixed pinion, e , around the center line of which the disk e' can be turned. The disk e' is rotated by the pulling of a strap or ribbon, f , which is wound upon the barrel d , fixed to the disk e' . The spring h in the barrel d is wound up by the pulling of the ribbon f , and it will turn back the barrel and the disk e' as soon as there is no more pull on the ribbon f .

When the disk e' rotates, the arm m comes in contact with the teeth of the pinion e , and thus causes the hammer i , the nose i' of which catches into a notch, m' , of the arm m , to strike the bell k . The hammer i will strike the bell when the disk e' rotates either way, Fig. 1.

If the gong shall sound while the disk e' is rotating in but one direction, the arm m has to be moved sidewise by means of the handle m^2 , so that the arm n , and not the arm m , will come in contact with the teeth of the pinion

e , Figs. 2 and 5. The arm n is on top of the arm m and pressed down by the action of the spring o . The noses n' of the arm n are placed in the notches m' on the upper side of the arm m , Figs. 6, 7, and 8. The small arm n^2 will then strike the cam i' of the hammer i if the disk e' rotates in the corresponding direction, (see position as shown in Fig. 2 by dotted lines,) and will ring the bell. If the disk e' , however, turns the other way, the lever n is moved in such a way that its arm n^2 will not lift the cam i' .

If the gong shall not sound at all, the handle m^2 is moved in the opposite direction, Fig. 3. Neither the arm m nor the arm n will come in contact with the teeth of the pinion e .

In Fig. 10 the apparatus is shown fastened to a door-frame, A. The door B carries a stud, C, where the outer end of the strap f is attached. By this arrangement the bell will ring if the door is moved either way; or it will ring if the door opens, and will not sound if the door closes, or the bell will not ring at all.

Having now particularly described and ascertained the nature of my said invention and in what manner the same is to be performed, I declare that what I claim is—

1. In an alarm apparatus, the combination, with the disk e , having the barrel cast therewith, of the spring on said barrel and strap connected therewith, a bell, and pivoted gravity-hammer actuated from the movement of the disk, substantially as set forth.

2. In an alarm apparatus, the combination, with the movable disk, spring-barrel, and strap for actuating the same, of a bell and pivoted gravity-hammer and an adjuster located on the outer face of the disk, as described, the said adjuster for varying the striking operation for either or both movements of the disk, substantially as set forth.

In testimony that I claim the foregoing as my invention I have signed my name, in presence of two witnesses, this 25th day of April, 1887.

WILHELM FRIEDRICH LÖFFELHARDT.

Witnesses:
